UNITED STATES PATENT OFFICE.

WINFRED H. JUERGENS, OF CLEVELAND, OHIO, ASSIGNOR TO THE H. J. McCUE COMPANY, OF CLEVELAND, OHIO, A CORPORATION OF OHIO.

ADJUSTING PLUG FOR MEASURING CHAMBERS.

Application filed October 30, 1922. Serial No. 597,865.

To all whom it may concern:

Be it known that I, WINFRED H. JUERGENS, a citizen of the United States, and a resident of Cleveland, county of Cuyahoga, 5 and State of Ohio, have invented a new and useful Improvement in Adjusting Plugs for Measuring Chambers, of which the following is a specification, the principle of the invention being herein explained and the best 10 mode in which I have contemplated applying that principle, so as to distinguish it from other inventions.

The present invention relates to an improved adjustable measuring plug which 15 may be used in various containers, valve chambers and the like for the purpose of varying the available content of such chamber and in this way adjusting the content of the chamber as may be desired. It is particularly adapted for use in measuring 20 valves such as are used in draft arms for soda fountains where a measured amount of syrup is to be discharged into the glass for the making of the beverage with carbonated water. In such cases it is highly desirable to be able to vary within certain 25 limits the amount of extract which is discharged, because of the varying sizes of glasses which are used. To the accomplishment 30 of the foregoing and related ends, said invention, then, consists of the means herein-after fully described and particularly pointed out in the claims.

The annexed drawing and the following 35 description set forth in detail certain mechanism embodying the invention, such disclosed means constituting, however, but one of various mechanical forms in which the principle of the invention may be used.

40 In said annexed drawing:—

Fig. 1 is a central longitudinal section through a chamber in which my adjustable plug (in elevation) is received; Fig. 2 is a central longitudinal section through my improved plug; Fig. 3 is a section on the line 3—3, in Fig. 2; and Fig. 4 is an end elevation of the same.

In Fig. 1 I have shown a chamber 1, in which is mounted my improved adjusting 50 plug 2, this figure being shown for the purpose of illustrating the operation of the plug. The plug itself consists of a core 3 and a removable cylinder 4 mounted on the core 3

and movable lengthwise thereof to increase or decrease the entire volume of the plug as 55 a whole. It will be evident that movement of plug 4 to the right, as shown in Fig. 1, will increase the overall length and bulk of the plug, and will correspondingly decrease the amount of liquid which can be held in 60 the chamber 1. Also by moving the plug 4 to the left, the capacity of the chamber 1 is increased.

The construction of the plug is shown in Fig. 2. It consists of a bolt 5 provided 65 with an enlarged head 6 and threaded outer end 7. This bolt is received in a core 8 which is spaced from the threaded portion of the bolt 7 to receive therebetween a coil spring 9 which operates against a shoulder 10 on the 70 core, and the head 11 on the tubular cylinder 4, which fits snugly, but slidably, over the outer wall of the core 8. Relative rotation between the cylinder 4 and the core 8 is prevented by the engagement of a turned-down 75 lug 13 on the cylinder in a slot 14, formed in the core 8 parallel with the axis thereof.

The head of the member 8 is provided with an enlarged flange 15, which is recessed on its inner face to receive a washer 16, 80 which is pressed snugly against the wall of the chamber 1, in which the plug is inserted to make a liquid-tight joint. A second washer or packing 12 is mounted between the head of the bolt and the core 3. The head 6 of the bolt 5 is provided with the usual slot 18, in which a screw driver may be inserted for turning this bolt, and in this way adjusting or varying the volume or bulk of the 85 plug as may be required.

90 The operation of my plug is as follows:— It is first inserted into the wall of the measuring chamber in the manner indicated in Fig. 1. Adjustment of the screw 5 will then force the cylinder 12 outwardly or inwardly, depending upon the direction of rotation of the screw 5, and as this cylinder cannot turn, because of the engagement of the lug 13 in the slot 14, it must move longitudinally, and in this way any desired adjustment may be given to the over-all length and volume of the plug.

95 Other modes of applying the principle of my invention may be employed instead of the one explained, change being made as regards the mechanism herein disclosed, pro- 100 105

vided the means stated by any of the following claims or the equivalent of such stated means be employed.

I therefore particularly point out and distinctly claim as my invention:—

1. An adjustable measuring plug comprising a body member provided with means adapting the same to be engaged in the wall of a chamber, a tubular cap slidably and snugly fitting over the same, and means adapted to variously position said cap with respect to said member.
2. An adjustable measuring plug comprising a body member provided with means adapting the same to be engaged in the wall of a chamber, a tubular cap slidably but non-rotatably engaging over said body member, and means adapted to variously position said cap with respect to said body member.
3. An adjustable measuring plug comprising a body member provided with means adapting the same to be engaged in the wall of a chamber, a tubular cap slidably but non-rotatably engaging over said body member, and an adjusting screw rotatably mounted

in said body member, said screw also engaging said cap and being adapted to vary the position of the same with respect to said body member.

4. An adjustable measuring plug comprising a body member provided with a threaded portion at one end adapting the same to be engaged in the wall of a chamber, said member having an opening longitudinally therethrough, a tubular cap, said cap engaging slidably but non-rotatably over said body member and having a threaded opening aligned with such opening through said body member, a bolt extending through such opening in said body member and engaging in such threaded opening in said cap, said bolt being rotatable from outside of said body member to variously position said cap with respect to said body member, and a spring disposed between said cap and body member, said spring acting on said bolt to hold the same snugly in said body member.

Signed by me, this 24 day of October, 1922.

WINFRED H. JUERGENS.
